UNITED STATES PATENT OFFICE.

JOHN BARNES GOODWIN, OF ELKO, NEVADA

GAS PRODUCER.

Application filed April 14, 1923. Serial No. 632,084.

To all whom it may concern:

Be it known that I, JOHN BARNES GOODWIN, a citizen of the United States, and a resident of Elko, in the county of Elko and State of Nevada, have invented certain new and useful Improvements in Gas Producers, of which the following is a specification.

My invention relates to improvements in apparatus for producing gas and it consists of the constructions, combinations and mode of operation herein described and claimed.

A further object of the invention is to provide both an apparatus for and process of producing gas.

Another object of the invention is to provide a gas producer for gasifying shale having an inner hollow column which distributes the fire in a comparatively narrow ribbon which can more readily be controlled, other means being provided for injecting air and steam in the center of said column preheating both these gases before they enter the retort and extracting some of the heat in the column.

A further object of the invention resides in the provision of pyrometers both in the outer wall of the producer and in the wall of the inner hollow column, furnishing a ready reference as to the temperature of the fire thereby enabling a more certain control.

Other objects and advantages will appear in the following specification, reference being had to the accompanying drawings, in which:

The view is a central vertical section of a gas producer constructed in accordance with the invention, some of the parts being shown diagrammatically.

In carrying out the invention, provision is made of an outer casing 1 which has an insulating lining 2. This lining preferably consists of the ordinary fire brick but may consist of any other material suitable for the purpose. The casing 1 is usually round but obviously may be square or any other desired shape. The casing has a frusto-conical top 3 into which the fuel inlet pipe 4 extends. The pipe 4 has a control damper 4a.

The fuel inlet pipe reaches down far enough into the interior of the retort to leave a sufficiently large space 5 adjacent to the top 3 when the retort is completely

filled with fuel F as shown. Gas is formed in the retort and passes up through the mass of fuel until it reaches the space adjacent the top 3 whence it escapes at the gas outlets 6.

Located in the center of the producer is a circular casing 7 around which fire brick or other insulation 8 is built as suggested by the drawing. The fire brick linings 2 and 8 face each other in the circular fuel zone 9. The inner casing 7 is covered by a conical hood 10. Both the outer and inner casings of the retort are in practice supported upon any suitable foundation. This is not shown in the drawings as it is regarded unnecessary for the understanding of the principles of the invention.

A grate 11 is situated around the bottom of the circular fuel zone for the obvious purpose of supporting the fuel. In practice, this grate will be of the mechanically operated type, the function of which is to continually discharge the incombustible residue of the fuel, dropping it into the ash pit 12. The ash pit has a control valve 12a. This ash pit is disposed at an angle to the horizontal, thereby causing the ashes to move down and away from the grate by gravity. The grate 11 is shown provided with projecting rods 13 merely for the purpose of suggesting the movable feature thereof. As stated before, the drawing is diagrammatic in some respects. The showing of the grate is diagrammatic, as the illustration of an automatic stoker would involve the showing of details which are not essential to the understanding of the operation of the producer.

Extending into the center of the hollow column 7 is the gas, steam and air inlet conduit 14. This conduit passes down through the ash pit and to the source of gaseous fluid supply. The end of the inlet conduit 14, which carries the combustion supporting gaseous fluid, extends into the hollow column 7 approximately one-half the length thereof, thereby providing a fluid chamber 15 of ample proportions having a solid top 10. A steam injector 16 enters the conduit 14. The steam or other gas mixes with the air in the conduit 14 and also acts as a cooling agent to the hollow column 7 as it passes through the chamber 15 and down in the direction of the arrows.

Pyrometers 17 and 18 are fitted in the walls of the outer and inner casings 1 and

7 respectively. These pyrometers furnish indications of the temperature of the fire both near the outer casing and near the center. By means of the indications thus obtained, the temperature may be kept as desired, that is to say, the air and steam are regulated in volume according to the requirement of the fire.

The operation is as follows: a fire is first built on the grate 11, and when properly started, is covered with fuel which is introduced by the pipe 4. This fuel consists of oil shale from which it is proposed to extract the gas. The gas producer is filled with shale until the interior looks substantially as shown in the drawing, the space 5 being left vacant for the more ready accumulation of gas. Air is supplied for combustion through the conduit 14, steam being injected at the pipe 16. The mixture of steam and air enters the chamber 15 where some of the heat of the walls of the hollow column 7 are absorbed thereby, carried downward due to the solid top 10^a to the space beneath the grate 11, then upward through the fire and shale body. The mixture of steam and air in the chamber 15 acts as a cooling agent for the hollow column. Furthermore, the steam acts as a conveyor of heat which it absorbs in passing through the fire zone and transfers it to the shale above heating it to distilling temperatures. By the time that the shale has dropped to the dotted line M all of the gases have been driven off and the carbon remaining in the shale furnishes fuel for the fire and is burnt in the fire zone below the line M. Other shale is then introduced at the pipe 4, whereupon the foregoing process is repeated.

Emphasis is laid on the fact that the fire zone is of circular configuration, by virtue of the fact that the hollow column 7 is in the center, thus defining a comparatively narrow ribbon of fire in respect to which the exact temperature is not only ascertainable but which is also capable of careful control. The control of combustion in the fire zone is accomplished by the proper regulation of air and steam or gas at the conduit 14 and pipe 16. These fluids after leaving the upper open end of the conduits 14 issue from the bottom of the hollow column 7 and are evenly distributed for passage up through the grate 11.

While the construction and arrangement of the improved gas producer as herein described and claimed, is that of a generally preferred form, obviously modifications and

changes may be made without departing from the spirit of the invention or the scope of the claims.

I claim:

1. A gas producer comprising a casing having a frusto-conical top with gas outlets, a fire brick lining in the casing up to the base of the frusto-conical top, a hollow column in the center of the casing having a fire brick lining therearound opposite the casing lining the column defining a comparatively narrow annular fire zone, a conical solid top on said column adapted to distribute fuel into said zone, a fuel pipe extending in the top of the casing sufficiently far to define a gas space between the top of the fuel and said gas outlets, a grate at the bottom of said fire zone for supporting the fuel, an ash pit for receiving the ash, a conduit extending into the hollow column for delivering combustible supporting gaseous fluids said fluids flowing out of the bottom of the column and being equally distributed before flowing into the casing through said grate, and a steam injector extending into said conduit for preheating the fluids.

2. A gas producer comprising an outer casing and an inner casing defining a fuel space between the two casings, a grate supported by the casing, a lining of fire resistant material provided on the inner wall of the outer casing and on the outer wall of the inner casing, means for supplying a heated combustion supporting gaseous fluid to the inner casing which is distributed to the fuel between the inner and outer casings, pyrometric means embedded in the walls of the inner casing and the walls of the outer casing for maintaining a constant temperature within the gas producer, and means for discharging the gases produced from the fuel.

3. A gas producer comprising an outer casing and an inner casing defining a fuel space between the two casings, a grate supported by the casing, a lining of fire resistant material provided on the inner wall of the outer casing and on the outer wall of the inner casing, means for supplying a heated combustion supporting gaseous fluid to the inner casing which is distributed to the fuel between the inner and outer casings, pyrometric means embedded in the walls of the inner casing and the walls of the outer casing for maintaining a constant temperature within the gas producer, and outlets for discharging the gases produced from the fuel.

JOHN BARNES GOODWIN.
